CONDENSATE DISPOSAL MEANS

Marion F. Knoy, Long Beach, Calif.

Application August 3, 1940, Serial No. 350,534

2 Claims. (Cl. 62—115)

My invention relates to refrigerating systems with special reference to air conditioning apparatus, and is directed to an improved means for disposing of water derived from the air in the operation of such apparatus.

The cooling of air by an air conditioning apparatus of the type under consideration is accomplished by passing the air in a stream over the surfaces of a cold element or evaporating coil maintained at substantially under the temperature of the air. In air-cooling practice, a temperature differential of 20° to 30° F. is sought and the temperature of the cold element is often below the dew point of the air for extended periods of time, the result being the continuous condensation of water from the air upon the surfaces of the cold element. To avoid damage to parts of the cooling apparatus or to furnishings adjacent the cooling apparatus some drip-catching or drainage expedient is required. Conditions commonly prevalent in hot weather cause rapid condensation and in the absence of adequate disposal means the water soon accumulates to a formidable quantity.

In many systems drainage to a sewer is not feasible or if feasible would be disproportionately expensive. In such installations it is necessary either to provide drainage receptacles to be emptied manually from time to time or to convey the condensates to the hot side of the refrigerating system for dissipation into the air that is separately circulated on that side of the system. My invention is directed to this latter disposal arrangement.

Experience in this field demonstrates that simple exposure of the superfluous water to the normal air flow on the hot side of the refrigerating system cannot be relied upon for disposal; the maximum rate of evaporation is never adequate for peak water loads. Various expedients have been suggested in the prior art. One suggestion is to employ only the usual rate of air flow required for the refrigerating system and to restrict that air flow locally for high velocity in intimate contact with the water to be dissipated, the intent being to cause the air stream to entrain the water. The difficulty here, however, is that any such restriction tends to reduce the rate of air flow along the surfaces of the refrigerant condenser below the requirements of the refrigerating system. This difficulty leads to a second proposal in the prior art to provide blowers or fans far above the requirements for cooling the refrigerant on the hot side of the cycle, the additional air flow being used to

achieve sufficient velocity to sweep the water out of the disposal receptacle.

The general object of my invention is to provide means to dispose of water condensed from the air on the cooling side of a refrigerating system. More specifically, it is my object to provide for adequate water disposal by evaporation alone and to do so by structural means requiring only normal air flow and only normal power consumption. Another object of my invention is to facilitate the cooling of refrigerant on the hot side of a refrigerating cycle thereby to raise the efficiency of the refrigerating apparatus. A still further object is to provide such a system in which it is not necessary to place the cold element of the refrigerating system higher than the refrigerant condenser.

Other objects and advantages of my invention will be apparent in my detailed description below, taken with the accompanying drawing.

Broadly described, my invention is based on the concept of transferring heat directly to the accumulated body of surplus water from the hot refrigerant on the compression side of the refrigeration system to attain a sufficiently high rate of vaporization to meet peak conditions. While an air stream across the body of water simplifies the problem, it is apparent that my method may be applied to any cooling system in the operation of which refrigerant is compressed, whether or not an air stream is available on the hot side of the system.

In the drawing which is to be considered as illustrative only:

Fig. 1 is a diagrammatic representation of an air-cooling apparatus incorporating my invention;

Fig. 2 is a transverse section taken as indicated by the line 2—2 of Fig. 1 showing the disposal receptacle in plan; and

Fig. 3 is a fragmentary view similar to Fig. 1 to illustrate a modification of my invention.

Fig. 1 is a diagrammatic layout of a typical air-cooling cabinet that is divided by an air-tight wall 45 into a cooling compartment 11 on the cold side of the refrigerating cycle and a compartment 12 on the hot side of the cycle. Refrigerant from a condenser 15 in the compartment 12 is conveyed by a pipe 16 to an expansion valve 17 in the compartment 11 and is released into a cold element or evaporating coil 20. A compressor 21 in the compartment 12 driven by a motor 22 draws the gaseous refrigerant from the evaporating coil 20 through a suction pipe 23. Upon being compressed in the compressor 21 and raised in tem-

perature because of the heat of compression, the refrigerant is conducted from the compressor to the condenser 15 through a pipe 25.

In accord with conventional practice a blower 26 in an air duct 27 driven by a motor 28 draws outdoor air into the compartment 12 over the surfaces of the various elements in the compartment 12 and discharges the air outdoors through the air duct. The current of outdoor air through the compartment 12 sweeps and eddies over the various surfaces to pick up heat from the condenser 15, the compressor 21, the pipe 25, and the two motors 22 and 28.

Indoor air moving in a current through the cooling compartment 11 passes over the evaporating coil 20 and in doing so yields moisture to the surfaces of the evaporating coil. The moisture forms droplets which are eventually caught in a drip pan 30 under the evaporating coil and water that tends to accumulate in the drip pan is conducted by a drainage pipe 31 through the wall 10 into a disposal receptacle 32 in the bottom of the compartment 12.

My invention as embodied here consists, first, in immersing a portion of the pipe 25 in the body of superfluous water 35 in the disposal receptacle 32 and, second, in directing the air stream in the compartment 12 over the surface of the body of superfluous water. As indicated in Fig. 2 the pipe 25, which contains superheated refrigerant gas, may be formed into a coil 36 in the disposal receptacle 32, the pipe being coiled to whatever length is necessary to achieve the required rate of heat transfer to the body of water 35.

As for the air stream through the compartment 12, various expedients may be employed to bring the air into intimate contact with the surface of the body of water 35. In the present arrangement, it will be noted that the inlet 31 of the air duct 27 is close to the upper edge of the disposal receptacle 32 and that flow of air along the body of water 35 in the disposal receptacle is further favored by a baffle 38 extending from the inlet 37 over the disposal receptacle. The air stream is heated before it reaches the disposal receptacle by contact with the condenser 15 and subsequent contact with the hotter surfaces of the pipe 25. The heated air stream attains a relatively high velocity at the disposal receptacle not only because the receptacle is relatively close to the inlet 37 but also because of the baffle 38.

In the disposal receptacle 32 the refrigerant in the pipe 25 loses part, if not all, of its superheat to the body of water 35. Under some operating conditions this superheat, together with the rapid flow of the heated air above the receptacle, is sufficient to keep the water in the receptacle down to insignificant volume. At higher rates of water condensation the residual body of water 35 in the disposal receptacle may increase to substantial volume but the increase will be limited because, in the first place, the higher the water level the larger the area of the pipe 25 in contact with the water and, in the second place, the length of the pipe 25 that is coiled in the disposal receptacle is designedly sufficient to cause a part of the refrigerant to liquefy whenever any substantial body of water is present to cool the coil. In liquefying, the refrigerant releases its latent heat of vaporization to expedite evaporation of the water in the disposal receptacle 32. One advantage of a single-channel coil in the disposal receptacle is that any

liquid formed in the coil is immediately carried over to the condenser 15 by the high velocity gaseous stream of refrigerant.

Since the pipe 25 in passing through the body 5 of water 35 participates in the necessary step 15 of removing the superheat and the heat of vaporization from the compressed refrigerant and thus takes some of the load of the condenser, it causes 20 not only solves the problem of water disposal but also increases the efficiency and capacity of the apparatus as a whole.

From an inspection of Fig. 1 it will be apparent 15 that it is not necessary that the evaporating coil 20 be higher than the condenser 15 since the only consideration in locating the evaporating coil is to provide drainage to the disposal receptacle 32 and the disposal receptacle is divorced from the condenser 15. In arrangements suggested heretofore for disposing of superfluous 25 water, the disposal receptacle is immediately under or immediately adjacent the condenser in the refrigerating system so that adequate drainage from the drip pan under the evaporating coil 30 may be achieved only by placing the evaporating coil at a level substantially above the level of the condenser. My apparatus may be readily adapted to any situation in which it is necessary or desirable to place the condenser at some level substantially above the evaporating coil.

The arrangement in Fig. 3 is in most respects identical with the arrangement in Fig. 1 as indicated by the use of like numbers to indicate like elements. The distinction in the arrangement of 35 Fig. 3 over the arrangement of Fig. 1 is in the substitution of a relatively deep disposal receptacle 40 for the relatively shallow disposal receptacle 32 and in the substitution of a relatively small auxiliary condenser 41 for the coil 36. The auxiliary condenser 41 assures the availability 40 of sufficient heat of vaporization from the refrigerant to vaporize the body of water 42 without danger of overflow.

The preferred forms and practices of my invention described in detail herein will suggest to 45 those skilled in the art various changes and substitutions that may be made without departing from my underlying concept; I reserve the right to all such changes and substitutions that 50 properly come within the scope of my appended claims.

I claim as my invention:

1. In an air-cooling apparatus having a refrigerating cycle including a compressor, a condenser, and an evaporator, the combination therewith of disposal means to vaporize water condensed on the outer surface of the evaporator, said disposal means comprising: walls forming an air course through the apparatus cut off from 55 said evaporator; power means to drive fresh air through said air course; a disposal receptacle to retain a body of water drained from the surface of said evaporator; and a fluid-passage means included in said refrigerating cycle in the hottest 60 zone thereof between the output side of the compressor and the input side of the condenser, said fluid-passage means having an exposed portion in said air course and a portion submerged in said body of water, said condenser being in said air course, said exposed portion of said fluid-passage means being in said air course downstream from 65 said condenser, whereby air flowing through said air course is initially heated by the warm surface of said condenser and is then heated further by the exposed portion of said fluid-passage 70 means.

means to lower the relative humidity of the air before the air reaches the water in the receptacle, said air course being locally restricted in cross section at said receptacle to accelerate the air flow across the surface of said body of water.

2. In an air-cooling apparatus having a refrigerating cycle including a compressor, a condenser, and an evaporator, the combination therewith of disposal means to vaporize water condensed on the outer surface of the evaporator, said disposal means comprising: walls forming an air course through the apparatus sealed off from said evaporator, said condenser and said compressor being in said air course; power means to drive fresh air through said air course; a disposal receptacle to retain a body of water drained from the surface of said evaporator, said receptacle being in said air course downstream from said condenser, there being a substantial extent of the air course between the condenser and the receptacle; and a fluid-passage means included

in said refrigerating cycle in the hottest zone thereof between the output side of the compressor and the input side of the condenser, said fluid-passage means including a first portion from the compressor to the receptacle, a second continuing portion submerged in the body of water in the receptacle, and a third continuing portion extending from the receptacle to said condenser, said first and third portions lying in said air course along said substantial extent of the air course, whereby air flowing through the air course is initially heated by the warm surface of said condenser and is further heated by the warmer surfaces of said compressor and said first and third portions of the passage means thereby to lower the relative humidity of the air before the air reaches the water, said air course being restricted in cross section at said receptacle to accelerate air flow across said body of water.
